UNITED STATES PATENT OFFICE.

ADOLFO SÁENZ YÁÑEZ, OF NEW YORK, N. Y.

INSTRUMENT FOR DIVIDING ANGLES.

SPECIFICATION forming part of Letters Patent No. 381,049, dated April 10, 1888.

Application filed October 16, 1886. Serial No. 216,419. (No model.)

To all whom it may concern:

Be it known that I, ADOLFO SÁENZ YÁÑEZ, (a subject of the King of Spain,) of Havana, Cuba, at present residing in the city, county, 5 and State of New York, have invented a new and Improved Instrument for Dividing Sectors, of which the following is a full, clear, and exact description.

The object of my invention is to provide a new and improved instrument for dividing sectors and angles into equal parts, and I prefer to call the instrument a "polysector."

The invention consists of a plate provided with polysecting curves.

15 The invention also consists in various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a face view of my improvement for dividing angles or sectors into equal parts. 25 Figs. 2 and 3 are similar views showing polysecting curves of different forms.

The instrument is made of a thin plate, A, and is preferably provided with the semi-circle B, and having its center at C, through 30 which passes a diameter, D, which forms the base of the instrument. A second concentric semi-circle, a, is inside of the semi-circle B and unites at F and G with the base-line D. A number of polysecting curves, b, c, d, and e, are 35 arranged within the polysecting circle a and the base D, and the part between the semi-circle a and the first polysecting curve, b, is cut out of the plate A, and the space of the plate A between the polysecting curve c and the next 40 polysecting curve, d, is removed, and the space between the next curve, e, and the base-line D is similarly cut out, so that bands are formed the edges of which represent the said polysecting curves. All the bands thus formed 45 connect with a base-band, E, which extends below the base D. The polysecting curves terminate either with one end at a common point and at the base-line, as shown in Figs. 1 and 50 3, or in the semicircular band and at the base-line, as shown in Fig. 2.

The polysecting curves vary in form, but have a proportionate relation with each other

for each instrument; but the instrument can be provided with different forms of curves, as shown in the figures, in which Figs. 1 and 3 55 show almond and apple shaped curves, while in Fig. 2 I make use of hyperbolas to attain the same purpose.

The curve b in Fig. 1 is defined geometrically under the condition that any one of its points—for instance, O—produces the equation $\frac{\text{angle } F\text{oC}}{\text{angle } o\text{FC}} = \frac{6}{4} = 1\frac{1}{2}$. The curve c is similarly defined under the condition that the angle $\frac{F\text{pC}}{p\text{FC}} = \frac{7}{3} = 2\frac{1}{3}$. The curve d is defined angle $\frac{p\text{FC}}{r\text{FC}} = \frac{8}{5} = 1\frac{3}{5}$.

under the condition that the angle $\frac{F\text{qC}}{q\text{FC}} = \frac{8}{2} = 4$. The curve e is determined under the condition 70 that the angle $\frac{F\text{rC}}{r\text{FC}} = \frac{9}{1} = 9$.

In Fig. 2 the curves b, c, d, and e are similarly defined geometrically by one of its points—for instance, the curve b—under condition 75 that the angle $\frac{o\text{FC}}{o\text{CF}} = 2$. The curve c is determined under the condition that the angle $\frac{p\text{CF}}{p\text{FC}} = 3$; the curve d under the condition that the angle $\frac{q\text{CF}}{q\text{FC}} = 4$. The curve e is geometrically 80 determined under the condition that the angle $\frac{r\text{CF}}{r\text{FC}} = 5$.

In Fig. 3 the curves a, b, c, d, and e are similarly determined under the condition, for the curve a, that the angle $\frac{C\text{Fn}}{\text{angle } F\text{nC}} = \frac{5}{1} = 5$; the curve b under the condition that the angle $\frac{C\text{Fo}}{\text{angle } F\text{oC}} = \frac{4}{2} = 2$; the curve c under the condition that the angle $\frac{C\text{Fp}}{\text{angle } F\text{pC}} = \frac{3}{3} = 1$. This curve 95 is part of a circle which has its central point at C, the radius being F C. The curve d is defined under the condition that the angle $\frac{C\text{Fq}}{\text{angle } F\text{qC}} = \frac{2}{4} = \frac{1}{2}$; and the curve e is determined under the condition that the angle $\frac{C\text{Fr}}{\text{angle } F\text{rC}} = \frac{1}{5}$.

- A straight-edge, N , is preferably used in connection with the instrument, and is provided with a point in line with one of its edges and fitted into an aperture into the plate
- 5 A at the point F . A knob or button, N' , is fastened near the other end of the straight-edge and serves to swing the said straight-edge N over the front of the plate A , the point F being the axis.
- 10 The instrument is used as follows: When the angle OCP is to be divided into equal parts, then the instrument is placed over the angle with the point C on the intersection of the lines OC and PC , and the base D of the instrument is on the line PC . It will be seen that the line OC intersects with all the polysecting curves a, b, c, d , and e at the points n, o, p, q , and r , and the operator now places the straight-edge N on the point O and marks
- 15 with a pencil or other means the intersection of the straight-edge with the semi-circle a at the point 1 . The operator then swings the straight-edge N to the point p and marks the intersection of the straight-edge N on the semi-circle a at 2 . Then the straight-edge N is moved to the point q , and the point 3 is marked on the semi-circle a , after which the operator marks in a similar manner the point 4 by swinging the straight-edge to the point r . The
- 20 points $1, 2, 3$, and 4 are equidistant from each other on the part nG of the semi-circle a , and if the operator now removes the instrument and draws the lines $RC, R'C, R''C, R'''C$, then a division of the angle OCP into five equal angles is made, and a sector constructed on the said angle by drawing the respective arc is divided into five equal parts. The same angle, OCP , can also be divided into four equal angles or parts by the same instrument by
- 25 placing the latter in its former position and by marking the intersection of the straight-edge N with the point p at S on the polysecting curve b , and by then swinging the straight-edge to the point q and indicating the point S' on the same polysecting curve b , and by
- 30 then moving the straight-edge N to the point r and indicating the point S'' on the curve b . The instrument is then removed and the lines $SC, S'C$, and $S''C$ are drawn and the required division into four equal parts is obtained. The
- 35 angle is in a similar manner divided into three or two equal parts by indicating the respective points of the polysecting curves c and d in a manner similar to that described above.
- 40 To prove that the points $1, 2, 3$, and 4 divide the arc of the circle nG into five equal parts, Fig. 1, the following considerations will be sufficient: In the triangle FoC , formed in the curve b , we have $\angle oFC + \angle FoC =$
- 45 $\angle oCP$, for the reason that this last angle is the external angle, that in said triangle is opposite to the two first angles. Also, we have
- 50 $\angle FoC = \frac{6}{4} \angle oFC$ in consequence of
- 55 the geometrical definition of the curve b . From

the union of these two equations we deduce that $\angle oFC = \frac{4}{10} \angle oCP$, and as the angle oFC is one-half of the angle $1CG$, the final result is as follows: $\angle 1CG = \frac{4}{5} \angle oCP \dots 70$

(1). By means of analogous considerations with respect to the triangle pFC , formed in the curve c , in which $\angle pFC = \frac{3}{3}$, we reach 75

the following equation: $\angle 2CG = \frac{3}{5} \angle oCP \dots (2)$. In the curve d , a study of the same kind, considering that $\angle FqC = \frac{8}{2}$, shows that 80

angles $3CG = \frac{2}{5} \angle oCP \dots (3)$. Finally, in

the curve e , where we know that the $\angle FrC = \angle rFC = 85$

9 , the same reasoning gives $\angle 4CG = \frac{1}{5} \angle oCP \dots (4)$.

An examination of the above equations— $1, 2, 3$, and 4 —enables us to see that we have 90

$\angle nC1 = \angle 1C2 = \angle 2C3 = \angle 3C4 = \angle 4CG = \frac{1}{5} \angle oCP$, with which it is

evident that the arcs $n1, 12, 23, 34, 4G$ are equal to each other, and that each one is the fifth 95

part of the arc nG . It is to be observed that the first polysecting curves give the division into five parts, the second curve the division into four parts, the third division into three parts, and the fourth the division into two parts. All the divisions may be obtained simultaneously before removing the instrument.

The characteristic property of the polysecting curves a, b, c, d , and e consists in the constant 105 or invariable relation of two of the angles of the triangle formed by the lines which unite the two points F and C to any one point of the curves. In Figs. 1 and 3 this constant relation is established for all the curves between the angle opposite the common base FC and the angle which has its vertex in the point F . In Fig. 2 a constant relation is between the angles adjacent to the base FC . Hence it is seen that a constant relation exists between the two angles drawn 115 from F and from C to any two points located on any of the curves. For example: In the curve b , Fig. 1, the angle $oFC = \frac{4}{10} \angle oCG$,

and when the line sC is drawn it is found that the angle $sFC = \frac{4}{10} \angle sCG$. Now a deduction of the result of the two equations gives

$\angle oFC - \angle sFC = \frac{4}{10} (\angle oCG - \angle sCG)$ or $\angle oFs = \frac{4}{10} \angle oCs$, thus demonstrating the relation between the two angles.

As the angles $1F2, 2F3, 3F4$, and $4FG$ are 130

equal, as before stated, it follows that the four angles oCs , sCs' , $s'Cs'$, and s^2CG have a like relation to each other, all angles being the result of the property of the curve b in consequence

5 of the value of each angle being $\frac{10}{4}$ of the angle $1F2$. The three angles produced by the curve c each have a value of $\frac{10}{3}$ angle $1F2$,

10 and the two angles produced on curve d each have a value of $\frac{10}{2}$ angle $1F2$. As the angle

15 $1F2$ is equal to $\frac{1}{10}$ angle oCP , it results that each one of the angles obtained by means of

20 the curve b has a value of $\frac{10}{4} \times \frac{1}{10}$ angle oCP or $\frac{1}{4}$ angle oCP , and each angle of those pertain-

25 ing to curve c has a value of $\frac{1}{3}$ angle oCP , and each angle of those belonging to the curve d has a value of $\frac{1}{2}$ angle oCP .

It will thus be seen that when an instrument is provided with a larger number of polysecting curves—say fifty, for instance—then the instrument is capable of dividing an angle or 30 sector in the manner above described into fifty, forty-nine, forty-eight, or any number of equal parts between the numbers fifty and one.

The instruments represented in Figs. 2 and 3 are used in the same manner described in reference to Fig. 1.

Instead of using the straight-edge, a common ruler may be employed for the same purpose and in the same manner.

Having thus described my invention, what I 40 claim as new, and desire to secure by Letters Patent, is—

1. An instrument for dividing angles and sectors, consisting of a frame-plate having a number of bands, the edges of which are poly- 45 secting curves, substantially as shown and described.

2. An instrument for dividing angles and sectors, consisting of a frame having the edge D forming a base and provided with a num- 50 ber of bands, the edges of which are poly- secting curves, substantially as shown and described.

3. In an instrument for dividing angles and sectors, a frame having the edge D forming a 55 base and provided with a number of bands, the edges of which are polysecting curves, in combination with a straight-edge pivoted on the said frame, substantially as shown and described.
